CUP MAKING MACHINE

Henry B. Cooley, Kensington, Conn., assignor to
 American Paper Goods Company, Montclair,
 N. J., a corporation of New Jersey

Application May 24, 1933, Serial No. 672,541

20 Claims. (Cl. 93—39)

My invention relates to that class of machines which are employed for making cups for drinking and similar purposes from light, thin material, as for instance, paper, and an object of my invention, among others, is the production of a machine of this type that shall be rapid in the operation of making cups and that shall be particularly efficient in producing the cups.

One form of a machine embodying my invention and in the construction and use of which the objects herein set out, as well as others, may be attained is illustrated in the accompanying drawings, in which—

Figure 1 is a plan view of my improved cup making machine.

Figure 2 is a view substantially on a plane denoted by the dotted line 2—2 of Fig. 1 showing a portion of said machine.

Figure 3 is a view on enlarged scale in horizontal section on a plane denoted by the dotted line 3—3 of Fig. 2 of a portion of the machine, minus the lip forming mechanism.

Figure 4 is a similar view in vertical section on a plane denoted by the dotted line 4—4 of Fig. 1.

Figure 5 is a view on a still further enlarged scale in section through the outer end of a mandrel and the bottom inserting plunger illustrating the manner of applying cup bottoms to the mandrel.

Figure 6 is a similar view of a mandrel showing a cup body applied thereto.

Figure 7 is a view similar to Fig. 5 but illustrating the inturning of the bottom edge of the cup body to enclose a flange on the cup bottom.

Figure 8 is another similar view illustrating the position of a mandrel with the cup body and cup bottom thereon just before the final operation of securing the bottom in place.

Figure 9 illustrates the manner of finally securing the cup bottom in place.

Figure 10, sheet 2, is a detail view in section on a plane denoted by the dotted line 10—10 of Fig. 4.

In the accompanying drawings the numeral 10 denotes generally the supporting frame of my improved machine and 11 a table surmounting said frame and on which a turret 12 is rotatably mounted, said turret having mandrels 13 projecting radially from its edge to receive cup bodies thereon and bottoms in a recess in each end thereof, in a manner to be hereinafter described. A step-by-step rotating movement is imparted to the turret by a geneva mechanism comprising a driving member 14 having studs which enter slots in a driven member 15 of said movement in

a manner common to mechanism of this type and which will be readily understood by those skilled in the art without further explanation herein.

The driving member 14 is rotated as by means of intermeshing gears 16 upon a turret actuating shaft 17 having a gear 18 meshing with a gear 19 secured to a driving shaft 20 mounted in the supporting frame and driven from any suitable source, as for instance, a chain engaged with a sprocket wheel 21.

Each of the mandrels has a recess 22 in its outer end in which an ejector 23 is located and which is operated as by means of an ejector stem 24 projecting through the mandrel and into the turret and having at its inner end an ejecting finger 25 operated by an ejector cam 26 along which the finger sweeps as the turret is rotated, said ejector operating to remove the cups from the mandrels after the bottoms have been secured in place.

At a station designated herein as *a* a cup bottom 27 is inserted in a recess 22 in a mandrel as by means of a cup inserting plunger 28 operated in any suitable manner through a support 29, a further explanation concerning which is omitted herein as not necessary to a full understanding of my invention. Said plunger 28 forces a disk to comprise a cup bottom into the recess 22, a flange 30 having been formed on the disk, as shown in Fig. 5 of the drawings.

In the next one-step rotation of the turret to a station designated herein as *b* a blank is wrapped about the mandrel by mechanism not necessary to be described herein, and the previously mucilaged meeting edges are stuck together to form a cup body 31 with the bottom end thereof projecting beyond the outer end of the mandrel, and as shown in Fig. 6. Up to this point the ejector 23 remains in the bottom of the recess 22, and as shown in Fig. 5.

When the turret comes to rest after the next one-step movement thereof to a station designated herein as *c* the finger 25 is engaged by a cam 69 on a cam slide 70 located in a groove in the table 11 and timely operated by mechanism (not shown herein) to move the ejector outwardly and locate a cup bottom in position for assembly with the cup body. As the turret is again rotated the finger 25 passes from the cam 69 to the ejector cam 26 which is formed to retain the ejector in this position, as the finger sweeps along the cam, to the position shown in Fig. 7, thereby retaining the edge of the flange 30 a short distance inwardly of the end of the cup body. At this station *c* a clamp plate 32 having

a hole fitted to receive the end portion of the cup on the outer end of the mandrel is moved into contact with the cup body to clamp the latter securely in place, said clamp plate being mounted 5 on a slide 33 movable between guides 34 secured to the upper surface of the table 11 and held in place by gibs, as shown in Fig. 1, said slide being timely operated in any suitable manner to clamp the cup bodies on the mandrels when the latter 10 come to rest at this station *c*. Said clamp plate is supported upon rods slideable in the slide 33 and against springs 35 surrounding said rods and which springs force said plate into yielding engagement with the cup bodies, and as shown 15 in Fig. 1 of the drawings.

Immediately following the engagement of the clamp plate with the bottom of a cup body the springs 35 yield to permit further movement of the slide 33 and thereby engage a lip forming 20 die 36, also supported on the slide 33, with the end of the cup body, projecting said end into a groove 37 in the die and thereby turning a lip 38 on the end of the cup body to enclose the flange 30 on the cup bottom, and as shown in 25 Fig. 7. In this operation of turning said lip the die may be rotated as by means of a belt or belts passing around pulleys 39 secured to a shaft 40 which supports said die.

After the lip 38 has been turned on the bottom 30 edge of the cup body and the flange 30 has been enclosed within said lip the slide 33 is withdrawn by the mechanism which advanced it, thereby releasing the clamp plate and die from the cup body and mandrel, permitting the latter, in the 35 next one-step movement of the turret, to be located at a station designated as *d* herein. It is here remarked that the bottom edge of the cup blank has been daubed with mucilage in a previous operation and as shown at 41 in Fig. 6, 40 whereby the cup bottom is tightly secured in place in a manner now to be described. Immediately following the location of the mandrel with the cup body thereon and the cup bottom in the recess in the end thereof having its flanged edge 45 enclosed within the lip 38, as just described, a clamp 42 carried by a slide comprising rigidly connected blocks 43 having flanges 44 held by gibs 45 in sliding contact with a guide 46 is moved into engagement with the cup body, and as shown 50 in Figs. 4 and 9 of the drawings. Said guide is mounted on and secured to the table 11 and a sleeve 47 is rotatably mounted, as in bushings, in the blocks 43, said sleeve having a sheave 48 secured thereto and driven as by means of belts 55 49 from any suitable source of power which may be, if desired, an electric motor employed for the purpose of driving said sleeve, the same remarks applying as to the pulleys 39 for rotating the lip forming die 36. A spinner head 50 is secured to 60 the sleeve 47 and supports slides 51 mounted for radial movement in said head, preferably two of these slides being employed and each being pressed toward the center of the head as by means of a spring 52. Each of said slides bears a spinner 65 53 supported on an arbor projecting from the slide, and as shown in Figs. 4, 8 and 9 of the drawings, said spinners being supported upon ball bearings, as shown in Fig. 4.

The slides 51 at their adjacent ends are formed 70 with recesses which combined form a tapered cavity into which the tapered end of a slide actuator 54 projects said actuator being pressed into contact with the slides as by means of a spring 55 located within the sleeve 47. A spinner actuating 75 plunger 56 extends within the sleeve 47, project-

ing out of the rear end thereof and having a pin 57 engaged in a slot in the sleeve, and as shown in Fig. 4 of the drawings. A spring 58 is located on the plunger 56, one end of the spring resting against the end of the sleeve 47 and the opposite end of said spring resting against a grooved actuating head 59 secured to the plunger 56. An actuating lever 60 has a forked end with rollers engaged within the groove in the head 59, the opposite end of said lever being secured to an actuating shaft 61 mounted in brackets 62 secured to the under side of and projecting downwardly from the table 11. An arm 63 secured to the shaft 61 projects downwardly and has an actuating rod 64 secured thereto, the opposite end of said rod having a forked end straddling the driving shaft 20. A roller on said forked end of the rod 64 engages within a groove in a cam 65 secured to the shaft 20.

In operation, the actuating lever 60 is rocked by operation of the cam 65 and the connections therewith just described. As the upper end of the lever 60 is moved forward it exerts pressure through the spring 58 upon the sleeve 47 moving said sleeve and all parts mounted thereon forward 100 engaging the clamp 42 with the cup body upon the mandrel and to the position shown in Figs. 3, 4 and 9 of the drawings.

Springs 66 upon rods 67 extending from the slide comprising the blocks 43 now permit movement 105 of all of the parts just referred to with the exception of the clamp 42 and the slide engages with a stop 68, thereby preventing further forward movement of said members. Action of the lever 60 now forces the plunger 56 forward compressing the spring 58 and pushes the slide actuator 54 into the cavity formed by the recess in the ends of the slides 51 the spring 55 acting as a cushion for this movement. This separates the slides and moves the spinners 53 into contact with the lip 38 110 on the cup body thereby forcing the same tightly into contact with the flange on the cup bottom, securing the latter firmly in place. After this operation the lever 60 is retracted and the parts are moved to their normal positions and movement of the turret is permitted to bring a new mandrel with a cup body and bottom thereon into position for another operation just described. It will be noted that the stop 68 places the spinners 53 in proper position within the overturned edge 120 of the cup body, further operation of the lever 60 causing the slides to spread apart to press the spinners into contact with said overturned edge as above described.

As the turret moves the mandrels from the 125 station *d* to the station *a* the finger 25 passes into contact with an ejector returning cam 71 as shown in Figs. 3 and 4 of the drawings which places the ejectors in positions for a repetition 130 of the cup forming operation.

I claim:

1. A cup making machine including a recessed mandrel to receive upon its outer surface a cup body with its end projecting beyond the end of said mandrel, means within said recess for supporting a flanged cup bottom within said projecting end, means for overturning the edge of said projecting end to enclose the flange of said bottom, and means for pressing said overturned edge into close contact with said flange. 145

2. A cup making machine including a recessed mandrel to receive upon its outer surface a cup body projecting beyond the end of the mandrel, means within said recess for supporting a flanged cup bottom within said projecting end, means 150

- for overturning the edge of said projecting end to enclose the flange of said bottom, and means for exerting a spinning action to press said overturned edge into close contact with said flange.
5. 3. A cup making machine including a recessed mandrel to receive upon its outer surface a cup body projecting beyond the end of the mandrel, means within said recess for supporting a flanged cup bottom within said projecting end, a plunger 10 having a shallow groove in its outer bottom surface to overturn the edge of said projecting end to enclose said flange, and means for actuating said plunger.
4. A cup making machine including a recessed 15 mandrel to receive upon its outer surface a cup body projecting beyond the end of the mandrel, means within said recess for supporting a flanged cup bottom within said projecting end, a plunger having a shallow groove in its outer bottom surface 20 to overturn the edge of said projecting end to enclose said flange, means for actuating said plunger, and means for pressing said overturned edge into close contact with said flange.
5. A cup making machine including a recessed 25 mandrel to receive upon its outer surface a cup body projecting beyond the end of the mandrel, means within said recess for supporting a flanged cup bottom within said projecting end, a plunger having a groove to overturn the edge of said projecting end to enclose said flange, means for actuating said plunger, and means for exerting a spinning action on said overturned edge to press it into contact with said flange.
6. A cup making machine including a mandrel 35 to receive a cup body projecting beyond the end of the mandrel, means movably located within said mandrel for supporting a flanged cup bottom within said projecting end, a plunger having a shallow groove in its outer bottom surface to overturn the edge of said projecting end to enclose said flange, means for moving said plunger toward and away from said mandrel, and means for rotating said plunger with said overturned end engaged in said groove.
- 45 7. A cup making machine including a recessed mandrel to receive upon its outer surface a cup body projecting beyond the end of the mandrel, means within said recess for supporting a flanged cup bottom within said projecting end, a plunger 50 cooperating with said mandrel to secure said bottom in place, and a clamp movable with said plunger to engage said cup body and to permit movement of said plunger after said engagement.
8. A cup making machine including a recessed 55 mandrel to receive upon its outer surface a cup body projecting beyond the end of the mandrel, means within said recess for supporting a flanged cup bottom within said projecting end, a plunger cooperating with said mandrel to secure said 60 bottom in place, a clamp movable with said plunger to engage said cup body and to permit movement of said plunger after said engagement, and means for rotating said plunger in contact with the edge of said body.
- 65 9. A cup making machine including a recessed mandrel to receive upon its outer surface a cup body projecting beyond the end of the mandrel, means within said recess for supporting a flanged cup bottom within said projecting end, a spinner 70 head, spinners mounted on said head, means for moving said head toward and from said mandrel, and means for rotating the spinners within said flanged bottom.
10. A cup making machine including a recessed 75 mandrel to receive upon its outer surface a cup
- body projecting beyond the end of the mandrel, means within said recess for supporting a flanged cup bottom within said projecting end, a spinner head, spinners rotatably mounted on said head, means for moving said head toward and from said mandrel, and means for rotating said head. 80
11. A cup making machine including a recessed mandrel to receive upon its outer surface a cup body projecting beyond the end of the mandrel, means within said recess for supporting a flanged cup bottom within said projecting end, a spinner head, spinners mounted on said head, means for separating said spinners to secure said flanged bottom in place, and means for rotating said spinners. 85
12. A cup making machine including a recessed mandrel to receive upon its outer surface a cup body projecting beyond the end of the mandrel, means within said recess for supporting a flanged cup bottom within said projecting end, a spinner head, slides mounted on said head, spinners carried by said slides, means for separating said slides, and means for rotating said spinners within said flanged bottom. 90
13. A cup making machine including a mandrel to receive a cup body projecting beyond the end of the mandrel, means for supporting a flanged cup bottom within said projecting end, a spinner head, slides mounted on said head, spinners carried by said slides, a member engaged 100 with said slides to separate them, means for resiliently pressing said member into contact with the slides, and means for rotating said spinners within said flanged bottom. 105
14. A cup making machine including a recessed mandrel to receive upon its outer surface a cup body projecting beyond the end of the mandrel, means within said recess for supporting a flanged cup bottom within said projecting end of said mandrel, a spinner head, slides mounted on said 110 head, spinners carried by said slides, a member to separate said slides, a plunger to operate said member, a spring interposed between said plunger and member to resiliently resist pressure of said slides, and means for rotating said spinners. 115
15. A cup making machine including a recessed mandrel to receive upon its outer surface a cup body projecting beyond the end of the mandrel, means within said recess for supporting a flanged cup bottom within said projecting end, a spinner head, spinners mounted on said head, a support for said head, means for moving said support to engage said spinners within said flanged bottom, and means for rotating said spinners. 120
16. A cup making machine including a recessed mandrel to receive upon its outer surface a cup body projecting beyond the end of the mandrel, means within said recess for supporting a flanged cup bottom within said projecting end, a spinner head, spinners mounted on said head, a support for said head, means for moving said support to engage said spinners within said flanged bottom, and means for rotating said support to rotate said spinners. 125
17. A cup making machine including a recessed mandrel to receive upon its outer surface a cup body projecting beyond the end of the mandrel, means within said recess for supporting a flanged cup bottom within said projecting end, a spinner head, spinners mounted on said head, a support for said head, means yieldingly engaging said support to move it lengthwise to locate said spinners within said flanged bottom to resist lateral 130

4

movement of said spinners, and means for rotating said spinners.

18. A cup making machine including a mandrel to receive a cup body projecting beyond the end of the mandrel, means for supporting a flanged cup bottom within said projecting end, a spinner head, spinners mounted for lateral movement on said head, a support for said head, a slide upon which said support is mounted, a stop to limit the movement of said slide, means yieldingly engaging said support for moving it lengthwise to locate said spinners within said flanged bottom, and means for rotating said head.

19. A cup making machine including a mandrel to receive a cup body projecting beyond the end of the mandrel, means for supporting a flanged cup bottom within said projecting end, a spinner head, spinners mounted for lateral movement on said head, a support for said head, a slide upon

20

which said support is mounted, a stop for said slide, means yieldingly engaging said support to move it lengthwise to locate said spinners within said flanged bottom, and means for rotating said support.

20. A cup making machine including a mandrel to receive a cup body projecting beyond the end of the mandrel, means for supporting a flanged cup bottom within said projecting end, a spinner head, slides mounted for lateral movement on said head, spinners mounted on said slides, a sleeve to support said head, actuating means projecting through said sleeve to separate said slides, said actuator being engaged with said sleeve, means resiliently engaging said sleeve to force it lengthwise to locate said spinners within said flanged cup bottom, and means for rotating said sleeve.
